(57) **CLAIM**

The ornamental design for a hair drying wrap, as shown and described.

DESCRIPTION

FIG. 1 is a front right perspective view of a hair drying wrap;

FIG. 2 is a rear right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front perspective view of the design of FIGS. 1-8 while being worn; and,

FIG. 10 is a rear perspective view thereof.

The broken lines showing a person's head and neck in FIGS. 9 and 10 illustrate the environment in which the design is used and form no part of the claimed design. The stippling shown in the drawings represents a texture on the surface of the claimed design.
